UNITED STATES PATENT OFFICE.

SAMUEL W. LUITWIELER, OF ROCHESTER, NEW YORK.

CAM-DRIVEN PUMP.

Application filed October 6, 1922. Serial No. 592,889.

To all whom it may concern:

Be it known that I, SAMUEL W. LUITWIELER, a citizen of the United States of America, residing at Rochester, in the county of Monroe and State of New York, have invented certain new and useful Improvements in Cam-Driven Pumps, of which the following is a specification.

My invention relates to a cam driven pump, more particularly to the class of pumps intended for domestic or other small capacity purposes, and it has for its purpose to afford a compact and simplified arrangements of parts which can be manufactured at a minimum cost.

A further purpose of the invention is to provide a mechanism which can be readily and thoroughly lubricated, and which lends itself to a pump of high efficiency, from which water or other liquid can be delivered in a continuous steady flow at practically constant volume and pressure without pulsation or vibration, regardless of the speed at which the pump is driven, and without necessity of an air chamber.

The invention also comprehends other objects and advantages, all of which will be apparent from the following description, in conjunction with the accompanying drawings, the novel features being pointed out in the claims following the specification.

In the drawings:

Figure 1 is a side elevation, partly in section, illustrating a pump with a preferred embodiment of the invention incorporated therein;

Figure 2 is a horizontal sectional view on the line 2—2 of Figure 1;

Figure 3 is a transverse vertical sectional view on the line 3—3 of Figure 1;

Figure 4 is a transverse vertical sectional view on the line 4—4 of Figure 1, and

Figure 5 is a perspective view of the cam-actuated member.

Referring more particularly to the drawings, in which like reference numerals refer to corresponding parts throughout the several views, 1 designates a conventional type of pump, with the usual inlet and outlet valves, mounted upon a base 2. The pump includes a piston 3 carried by the piston rod 4 which reciprocates through a stuffing box 5. The piston rod 4 is connected to a cam-actuated member that is located and operated in the manner now to be described.

On the base 2 is a cam housing of gen-

erally circular form, and comprising a stationary part 6, formed integral with the base 2 and a removable end portion 7 adapted to be attached to the body portion of the housing by the set screws 8. The sides of the housing are preferably flat and provided with bearings 9 which support a divided cam shaft 10 on which is fixedly mounted the cam 11. The cam 11 rotates with the shaft 10, travelling around the circular housing, and cooperates with a cam-actuated member that is connected to the piston rod 4.

The cam-actuated member is preferably of integral formation and cylindrical in form, as illustrated in Figure 5, and includes the end portions 12 and 13, and the central portion 14, which is slotted in right angled planes, the vertical slot 15 serving to receive the cam 11, and the horizontal slot 16 to receive the cam shaft 10, and to permit the cam-actuated member to reciprocate upon the cam shaft. The piston rod 4 is attached to the cam-actuated member in any convenient manner as by threading it therein, and to insure rectilinear travel of the cam-actuated member, the cam housing is provided at its opposite ends with cylindrical collars 17 and 18 affording cylindrical openings or guideways that guide the end portions 12 and 13 of the cam-actuated member.

The end portions 12 and 13 are formed solid at their inner extremities, and are preferably hollow at their outer extremities, by which arrangement the end portion 12 is permitted to travel over the stuffing box 5 during its reciprocating movement, thus making it possible to arrange the parts in a small compass. By forming the outer parts of the end portions of the cam-actuated member hollow, a lighter construction is also afforded which tends both to reduce the cost of the mechanism as well as increasing its efficiency.

The end portions 12 and 13 of the cam-actuated member are provided with transverse openings or bearings 19 and 20 within which are mounted the rollers 21 that engage the periphery of the cam, whereby the cam-actuated member is reciprocated by the rotation of the cam and cam shaft. 22 designates a plug or closure for an opening at the top of the cam housing to permit filling the latter with a lubricant, while 23 is a drain plug for the lubricant, and in order to prevent

the lubricant from working outwardly at the ends of the housing, suitable packings 24 are employed, which are held in place by the removable rings 25. The guideways for 5 the cam actuated member are in direct alignment with the piston rod 4, thus insuring accurate movement, and a straight line travel of the piston rod, while all the parts of the cam mechanism are thoroughly lubricated by placing within the cam housing the necessary amount of lubricant, which is splashed and brought into intimate contact with all the moving parts by the rotation of the cam.

15 While I have described the invention with reference to a particular embodiment, it is not to be understood as limited to the precise details or arrangement disclosed, but this application is intended to cover any 20 modifications or departures from the structure set forth that may come within the intended purposes of the improvements or the scope of the following claim.

I claim:
25 The combination with a cam housing hav-

ing collars at its opposite ends affording relatively large circular openings constituting guideways, of a cam rotatable in the housing, a cylindrical one-piece cam-actuated member including relatively large cylindrical end portions which are hollow and travel in the aforesaid guideways, a piston rod connected to one of said end portions, a stuffing box surrounding said piston rod and adapted to be received by the adjacent hollow end portion as the latter moves toward the stuffing box, a cam shaft on which the cam is fixed, the cam-actuated member also including a cylindrical central portion formed integral with said end portions and slotted in right-angled planes to receive the cam and cam shaft respectively, the cam-actuated member having cylindrical transverse openings extending parallel to the cam shaft, and rollers journaled in said openings and engaging opposite points of the cam.

In witness whereof, I have hereunto signed my name.

SAMUEL W. LUITWIELER.
